UNITED STATES PATENT OFFICE.

ANTON GOEMANN, OF BALTIMORE, MARYLAND, ASSIGNOR OF ONE-HALF TO PAUL A. BOEKEL, OF BALTIMORE, MARYLAND.

FUSE PLUG.

Application filed December 22, 1924. Serial No. 757,430.

To all whom it may concern:

Be it known that I, ANTON GOEMANN, a citizen of the German Republic, residing at Baltimore, in the State of Maryland, have 5 invented a new and useful Improvement in Fuse Plugs, of which the following is a specification.

The invention relates to fuse plugs, and has as an object the provision of a fuse plug 10 provided with a plurality of fusible elements which may be successively brought into use.

A further object of the invention is the provision of a multiple fuse plug of great simplicity.

15 A further object of the invention is the provision of a multiple fuse plug provided with a minimum number of parts, and which may be readily assembled.

Further objects of the invention will appear 20 from the following description when read in connection with the accompanying drawings, wherein:

Fig. 1 is an end view partly broken away.

25 Fig. 2 is a central section on line 2—2 of Fig. 1.

Fig. 3 is a transverse section on line 3—3 of Fig. 2, and

30 Fig. 4 is a detail vertical section on line 4—4 of Fig. 1.

As shown, the device comprises a body 10 of insulating material, a portion of its outer wall being formed into spiral corrugations to provide a screw thread and having 35 a metal shell 11 closely fitted thereto. The plug thus provided is adapted to screw into a screw socket in the manner common to devices of this character, the shell 11 making electrical contact with the wall of the 40 socket.

Mounted in longitudinal passages 12, in the body 10, there are shown fusible elements 13, one end of each of which is secured in electrical contact with the shell 11 45 as by soldering. The upper end of each fusible element 13 is shown as secured to a plate 14, each plate housed in a depression 15 in the upper surface of the plug 10.

A central contact for the plug is provided 50 by the end of a rod 16, revolvably mounted in the plug 10, which plug is retained thereon as by means of the enlarged head 17 and washer 18. The head 17 is adapted to make contact with a central contact of a socket 55 in the well known manner.

To provide electrical connection between the rod 16 and the fusible elements 13, there is shown a plate 19 permanently assembled with the rod 16. This assembly may be accomplished by providing a reduced end upon 60 the rod 16, which passes through a central perforation in the plate 19, and the projecting end of the rod is then headed as shown at 20.

Connection between the plate 19 and a 65 chosen plate 14 may be provided by means of a tongue 21, struck downwardly from the material of the plate 19. The plate 19 is preferably formed of material such as spring brass and therefore when the disk-like head 22 of the plug is revolved, carrying with it the plate 19, the tongue 21 will be pressed out of one depression, and, upon further revolution, will spring into contact 70 with the next plate 14 of the series. 75

The disk 22 is shown as rigidly secured to the plate 19 during the assembly of the device. This may be accomplished in any desirable manner, but it is preferred to form the head 22 of initially plastic material and 80 to mold the plate 19 thereinto, and upturned margin 23 of the plate being shown for this purpose.

Obviously, other forms of anchorage to the disk 22 may be substituted therefor. 85

In the manufacture of the device, it is only necessary to assemble the plate 19 with the rod 16 prior to formation of the disk 22 with the assembled rod and disk permanently secured thereto during its manufacture. The assembly of the elements 13 with the plates 14, and their insertion in the perforations 12, is a simple matter after which the elements may be soldered to the shell 11. The disk 22 and rod 16 is then 90 assembled with the plug 10, thus constituting 95 the entire assembly of the device.

To enable the user to determine the setting of the device, numerals are shown upon the upper portion of the body 10, as at 24, 100 and an opening 25 is provided in the disk 22 for observation thereof. If the plug be set at numeral 1 when first placed in use, the user will be sure, when element 6 fails, that the plug is exhausted, when a new plug 105 may be substituted as in the single form of plug now in use.

Because of the compactness of the device, the multiple plug of the invention may be 110 freely substituted in any location where the

single form of plug is now in use, thus obviating a serious objection to other forms of multiple fuse plug of which I am aware.

In trials, to discover which plug has failed, all the plugs in a box may be revolved one numeral, and when the motion of the disk is found to reestablish a circuit, the plugs which have been needlessly disturbed may have the revolution of the disk 22 therewith completed to bring them back to the numeral which was showing at the beginning of the operation, whereby to not overlook a good fusible element.

A user may readily test out a plug upon purchase by inserting the same in a socket and passing each of the fusible elements in review before placing the plug into service.

Minor changes may be made in the physical embodiment of the invention without departing from the spirit thereof.

I claim:

1. A multiple fuse plug comprising, in combination, a body of insulating material having a plurality of longitudinal passages 25 concentrically arranged, and a depression about one of the openings of each passage, a metallic shell mounted on the surface of said body, a plurality of fusible elements mounted in said passages, each in electrical contact with said shell, a contact plate seated in each depression and in electrical

connection with the respective elements, a disk-like head of insulating material, a metallic disk secured to a surface of said head, a conductor secured to and projecting from said metallic disk journaled in the body and projecting therefrom to provide a central plug contact, a spring finger struck from the material of said disk and adapted to enter said depressions upon revolution of the head to place the contact plates in electrical connection with the conductor.

2. A multiple fuse plug comprising, in combination, a body of insulating material having concentrically arranged longitudinal passage adjacent its periphery, a screw-threaded metallic shell mounted on said body, a fusible element in each passage in electrical connection with said shell, contact plates carried by said body in electrical connection with the respective fusible elements, a disk-like head, a metallic plate having a deflected portion molded within said head to secure the plate permanently thereto, a conductor rigidly secured to the plate journaled in said body for free revolution and projecting therefrom to provide a central plug contact, a spring finger struck from the material of said disk adapted to make successive contact with said plates upon revolution of the head.

ANTON GOEMANN.
